A. CHISHOLM

COMBINATION PADLOCK

Filed Sept. 22, 1926

Fig. 1

Fig. 2

UNITED STATES PATENT OFFICE.

ALEXANDER CHISHOLM, OF WENATCHEE, WASHINGTON.

COMBINATION PADLOCK.

Application filed September 22, 1926. Serial No. 136,957.

My present invention relates to improvements in combination padlocks of the type utilizing a U-shape sliding shackle and rotary rings combined therewith. The primary object of the invention is the provision of a lock of this character which is adapted for many different uses, and is composed of a minimum number of parts to insure low cost of manufacture. The device is simple in construction and may be operated or manipulated with facility to render it free from unauthorized use.

The invention consists in certain novel combinations and arrangement of parts involving the rotary locking rings and slideable shackle as will be hereinafter more fully pointed out and claimed.

In the accompanying drawings, I have illustrated one complete example of the physical embodiment of my invention in which the parts are combined and arranged according to the best mode I have so far devised for the practical application of the principles of my invention.

Figure 1 is a view in side elevation of a combination padlock involving my invention;

Fig. 2 is a sectional detail view of the padlock showing by dotted lines the bars of the shackle in open position;

Fig. 3 is a transverse sectional view at line 3—3 of Fig. 2;

Fig. 4 is an enlarged detail sectional view showing the friction devices between the rotary rings and the body of the padlock; and

Fig. 5 is a cross sectional view of one of the rotary locking rings.

In carrying out my invention, I employ an interior body or core 1 having spaced heads 2 and 3 preferably of circular shape and riveted or otherwise rigidly secured at the opposite ends of the body as at 4. The round body and its heads 2 and 3 thus form a rigid structure upon which are mounted a number of rotary rings designated 5, 6, 7 and 8. The number of rings may be varied, and they are interposed between the two heads 2 and 3 of the padlock. The rings are independently rotatable and each ring is provided with an annular rib 9 on one face and a complementary groove 10 on its other face in order that adjoining rings may have the ribs and grooves in position to retain them in alinement and to guide them in their rotary movement. The head 2 is

fashioned with an annular groove 11 for a rib on ring 5, and the head 3 is fashioned with a complementary annular rib 12 to fit in a groove 10 of the rotary ring 8. In this manner, the rings which are interposed between the two heads are retained in position to be rotated independently of each other and of the two spaced heads. In Fig 1, it will be seen that the rings are provided on their exterior faces with lines 13 which may register with each other and also with complementary lines 14 on the fixed heads of the padlock, and numerals are provided on the rings and heads which may be alined for the purpose of providing a combination to permit unlocking of the padlock.

Frictional means are carried by the body of the padlock for retarding the rotary movement of the rings, and for this purpose the body 1 is provided with a number of spring blades 15 corresponding to the number of rotary rings, each blade being anchored at 16 in the body 1 of the padlock. The interior face of each ring is notched as at 17, and the free end of a spring 15 engages with these notched portions of the rotary ring to hold it in stationary position. It will be understood of course that the rotary rings may be freely rotated, but the spring detents 15 provide frictional engagement to retard the movement of the rings and to retain them in adjusted position.

Each rotary ring is fashioned with an interior annular flange 18 and each flange 18 is provided with a complementary notch 19. In addition to notch 19, each flange is provided with a series of false notches 20.

The shackle 21 is of U-shape and is designed to slide into and out of engagement with the operating parts of the padlock. Its two bars 22 and 23 are designed for insertion into the padlock, the bar 22 having transverse spaced notches 24 on its outer face, and the bar 23 having a longitudinal groove 25 on its outer face. The head 2 is provided with circular openings 26 and 27 for these bars, the body 1 of the padlock is provided with semi-circular grooves 28 and 29 for guiding the bars of the shackle, and the head 3 is provided with sockets 30 and 31 for the respective ends of the bars 22 and 23 of the shackle when it is inserted in locked position.

It will be understood that the rotary rings

are first brought into position with the notches 19 in alinement with each other and with the openings 26 and 30 of the respective ends. In this position the shackle may 5 be inserted and shoved down to operative position within the padlock as shown in Fig. 2, then by turning one or more of the rings the flanges 18 of the rings are turned in the complementary notches 24 of the 10 shackle, thus locking the shackle in the padlock. Thereafter, to restore the rings to position for alining their notches 19 in order to withdraw the shackle, the combination indicated on the exterior of the padlock is resorted to, and when thus alined the 15 shackle may be withdrawn.

Having thus fully described my invention,

what I claim as new and desire to secure by Letters Patent, is:—

The combination with a round body having 20 diametrically opposite longitudinal grooves and rigid heads on said body having openings and sockets therein, of a plurality of rotary locking rings interposed between said heads, complementary annular grooves 25 and annular ribs between said heads and said rings, a spring engaging each ring and having one end anchored to said body, a notched flange on each of said rings, and a U-shaped shackle for co-action with said 30 rings having transverse notches in one bar and a longitudinal groove in its other bar.

In testimony whereof I affix my signature.
ALEXANDER CHISHOLM.
